UNITED STATES PATENT OFFICE.

ARTHUR J. SWEET, OF ANN ARBOR, MICHIGAN, ASSIGNOR OF ONE-THIRD
TO GEO. W. SWEET AND SIDNEY SMITH, OF ANN ARBOR, MICHIGAN.

FEED-WATER HEATER.

SPECIFICATION forming part of Letters Patent No. 758,718, dated May 3, 1904.
Application filed May 4, 1903. Serial No. 155,474. (No model.)

To all whom it may concern:

Be it known that I, ARTHUR J. SWEET, a citizen of the United States, residing at Ann Arbor, county of Washtenaw, State of Michigan, have invented a certain new and useful Improvement in Feed-Water Heaters; and I declare the following to be a full, clear, and exact description of the invention, such as will enable others skilled in the art to which it pertains to make and use the same, reference being had to the accompanying drawings, which form a part of this specification.

This invention relates to feed-water heaters, and has for its object an improved feed-water heater intended to be used to utilize the heat of exhaust-steam for the purpose of heating water to be used in a boiler.

In the drawings, Figure 1 shows the heater used with a coil. Fig. 2 is a sectional view, 20 on an enlarged plan, of the upper part of the heater. Fig. 3 is a detail of the nozzle used. Fig. 4 shows a box form of structure employing the same invention. Fig. 5 is a cross-section of the device shown in Fig. 4. Fig. 6 25 is a plan view of the nozzle.

The heater consists, in substance, of a conductor for water and a means for mingling the exhaust-steam of an engine with the water in the conductor, after which the water is carried through a tortuous channel in which it deposits sediment and limey materials, and it is finally received in a tank from which it is introduced to the boiler by any approved means.

35 2 indicates the exhaust-pipe of an engine through which steam is escaping to the open air.

3 indicates a vertical pipe connected to the exhaust-pipe 2 by cross-pipe 4, which may be 40 provided with hand-valve 5 or may be left without such hand-valve. Into the pipe 3, below the junction of the cross-pipe 4, is inserted the end of a water-pipe 6. The terminal of the water-pipe 6 within the pipe 3 reaches upward to nearly the end of the cross-pipe 4 and is provided with a rose or spray-nozzle 7. Below the spray-nozzle 7 the pipe 3 leads to a deposit-chamber, and this deposit-chamber may be any long and preferably-tor-

tuous channel, along which the water travels 50 slowly and along which it deposits deleterious matter or matter injurious to the boiler and which will deposit from highly-heated water that is at rest or moving only slowly. In the form shown in Fig. 1 the tortuous channel is 55 a coil of pipe with horizontal sections a, b, c, d, and e, joined by suitable bends or elbows, and in the elbows are inserted plugs p, q, which may be removed, and access may be had through the openings to the interior of the 60 pipes to clean them out. Below the coil is a tank T, provided with a manhole t and with a yoke K and screws to hold the manhole-cover R in place. In the form shown in Figs. 4 and 5 a tank with baffle-plates is substituted for 65 the coil. The baffle-plates A, C, E, and G are secured to the back and the plates B, D, and F to the front of the tank, and the entire front, carrying plates B, D, and F, is removable in order that the structure may be cleaned. 70

In the form shown in Figs. 4 and 5 the water-tank may be at the bottom of the box. Both forms may be secured to the wall of a building in a way to occupy but little valuable space.

In operation a jet of water is thrown through the nozzle 7 from a source of supply that connects with water-pipes 6. This is thrown across the end of the pipe 3 into the extension 8 and drops down to the channel below the pipe 3. In dropping, the water that has been thrown into the channel carries down the air with it, producing a suction or partial vacuum and a consequent inflow of steam from the exhaust-pipe 2 into the heater. The water thrown 85 through the nozzle is preferably in a fine spray or in a divided state in a condition to be quickly and easily heated by the heat of the exhaust-steam, and it takes up a large volume of heat from the exhaust-steam. At the same 90 time it produces a draft or an entire absence of back pressure on the exhaust-pipe and aids instead of obstructing the engine in its work.

What I claim is—

1. In a feed-water heater, in combination 95 with the exhaust-pipe of an engine, a chamber, a spray-pipe leading from below and directed upward into said chamber, a connection from

the exhaust to the chamber whereby the spray is utilized to produce a draft from the exhaust-pipe, substantially as described.

2. In combination with the exhaust-pipe of an engine, a spray-chamber, a spray-pipe leading from below thereinto and directed upward across a steam-inlet, a pipe connecting the exhaust-pipe with the spray-chamber and providing said steam-inlet, a receptacle for water below the spray-chamber, and means whereby the weight of the water is utilized to produce a draft or a suction action on steam in the exhaust-pipe, substantially as described.
3. In a feed-water heater, in combination

with the exhaust-pipe of an engine, a spray-chamber, a spray-pipe leading thereinto, a pipe connection from the exhaust-pipe to the spray-chamber, a tortuous conduit for water emerging from the spray-chamber, and means for cleaning the tortuous chamber, substantially as described.

In testimony whereof I sign this specification in the presence of two witnesses.

ARTHUR J. SWEET
